UNITED STATES PATENT OFFICE.

JOSEPH F. LENNON, OF PAINESVILLE, OHIO.

VALVE-OPERATING MECHANISM.

Application filed March 12, 1923. Serial No. 624,487.

To all whom it may concern:

Be it known that I, JOSEPH F. LENNON, a citizen of the United States, residing at Painesville, in the county of Lake and State 5 of Ohio, have invented certain new and useful Improvements in Valve-Operating Mechanism, of which the following is a specification.

This invention relates to internal combustion engines, and more particularly to a valve-operating mechanism therefor.

This invention has to do particularly with a mechanism for operating valves known as the overhead type, that is, with the valves 15 arranged in the head end of the cylinders. Heretofore with known types of valve-operating mechanisms, considerable noise has been occasioned by the operation of the same, which in itself has made overhead 20 valves objectionable particularly in view of the fact that automobile manufacturers are particularly desirous of eliminating all unnecessary noises, thus rendering the operation of their engines as quiet as possible.

It is therefore, the particular object of my invention to provide a valve-operating mechanism which will eliminate a great portion 25 of the noise now occasioned by the operation of the valve and at the same time provide a suitable, positive and efficient action 30 of the valves at all times, and under all conditions.

Another feature of improvement in my invention is to provide a valve-actuating 35 mechanism which may be quickly and easily manufactured at a reasonable cost, and which may be easily installed and which can furthermore be repaired with facility.

The features of construction of my improved invention will be made more apparent as the description proceeds, especially 40 when considered in connection with the accompanying drawings, wherein,

Fig. 1 is a sectional view through an internal combustion engine showing my improved valve-operating mechanism,

Fig. 2 is a fragmentary sectional view taken substantially as indicated by the line 2-2 in Fig. 1,

Fig. 3 is a fragmentary sectional view taken substantially on the plane indicated by line 3-3 in Fig. 3, and

Fig. 4 is a separated perspective view of a portion of the valve-operating mechanism.

Referring now more particularly to the drawings wherein like reference characters

indicate like parts, it will be noted that there is illustrated an internal combustion engine comprising a cylinder 10, a piston 11, a crank case 12, a cam shaft 13, carrying a 60 cam 14. The reference character 15 indicates the valve which is normally closed by a spring 16 which bears on the one hand against a washer 17, and on the other against the head of the cylinder. In operation the 65 valve 15 is adapted to be depressed against the action of the spring 16, as will be readily apparent.

My improved valve-operating mechanism consists of a pull-bar or member 18 which 70 engages with one end 19 the valve 15, and with the other end 20 a guide rod 21 which is surrounded by the dummy spring 22, the strength of which is equal to the spring 16 of the valve. The rod 21 is guided in an 75 opening 23 formed in a bracket arm 24 extending from the engine body.

Connected to the bar 18 and centrally thereof is a member 25, preferably a flexible member such as a cable or the like. The 80 upper end thereof is threaded so as to be engaged by an adjusting nut 26, a lock-nut 27 being preferably provided to engage the underside of the bar 18.

Secured to the lower end of the cable 25 85 and preferably by welding, is a nut 28 which is adapted to engage a threaded portion 29 of a tappet 30. After connection is made between the cable 25 and the tappet 30 by means of a nut 28, the connection is locked 90 by means of a lock-nut 31.

The tappet 30 is half-moon shaped in cross section, the flat side 32 thereof being positioned away from the engine body as fully illustrated in Figs. 2 and 3, the cylindrical face 33 of the tappet engaging a similarly shaped recess formed in an enlargement 34 of the engine body. A guide-plate 35 is secured in place by bolts 36 which extend through apertures in the ends of this 100 guide-plate and are threaded into the engine body. Suitable adjustment of the guide-plate may be provided by inserting or removing one or more shims 37, as will be readily apparent.

Formed on the lower end of the tappet 30 is a ring member 38 which surrounds the cam shaft 13 and cam 14. Formed on the ring 38 and adjacent the lower portion thereof is a nipple or raised portion 39. 110 This nipple 39 is adapted to ride on the surface of the cam 14, thus reciprocating the

2
tappet 30 and exerting a downward pull on the pull-bar 18 to open the valve 15.

During the operation of the engine the cam shaft 13 and cam 14 are rotated and by reason of the engagement of the nipple 39 therewith, a downward pull is exerted on the cable 25 and consequently on the pull-bar 18. Inasmuch as the cable 25 is connected to the pull-bar 18, at the center of the latter an equal pressure is exerted on the springs 16 and 27, respectively. The strength of the dummy spring 22 is equal to that of the valve spring 16, so that when the downward pull is exerted on the bar 18, the bar will move downwardly, remaining however, in a horizontal position, thus opening the valve 15 against the tension of its spring 16. Obviously as the cam shaft 13 continues to rotate, the combined pressure of the springs 16 and 22 will move the bar 18 to its uppermost position, whereupon the valve 15 will again be closed.

The noise incident to the use of tappet rods and other similar operating means for controlling the valves, are therefore eliminated and the valve operates positively and efficiently with considerably less noise. The time at which the valve 15 closes may be varied by adjusting the nut 26 to vary the tension of the springs 16. Furthermore the tappet 30 may be adjusted by removing the guide-plate 35 and inserting or removing the shims 37 arranged between the plate and the engine body.

The construction of my improved valve-operating mechanism is simple, whereby it may be manufactured at a minimum cost, and because of the accessibility and small number of the parts, it may be easily repaired, or adjusted.

While one physical embodiment of my invention is described and illustrated herein, I do not intend to unnecessarily limit this invention, but reserve the right to make

such changes or modifications in the specific construction thereof as should come within the purview of the accompanying claims.

Having thus described my invention, what I claim is:

1. The combination with an engine having a spring closed valve in the head thereof and a cam shaft of a horizontally disposed pull-bar, one end of said pull-bar engaging the said valve, a dummy spring engaging the other end of said pull-bar, a flexible member connected to the center of said pull-bar, a half-moon shaped tappet guidingly supported adjacent the cam shaft of the engine, a cam ring carried by said tappet, a cam on said cam ring and engaging the cam of the engine cam shaft, said tappet being connected to said flexible member whereby said horizontally arranged pull-bar may be displaced vertically to operate said valve.

2. A valve operating mechanism for use in connection with an internal combustion engine having an overhead spring closed valve and a cam shaft and cam, said valve-operating mechanism comprising a horizontally arranged pull-bar engaging said engine valve with one of its ends, a dummy spring of equal strength arranged under the other end of said pull-bar, a half-moon shaped tappet guidingly supported adjacent the cam shaft of the engine, adjustable guiding means for said tappet, a cam ring connected to said tappet, a cam carried by said cam ring and engaging the cam of the engine cam shaft and a flexible member connecting said tappet to the center of said pull-bar whereby said pull-bar may be displaced vertically against the combined strength of the valve spring and dummy spring.

In testimony whereof I affix my signature.

JOSEPH F. LENNON.
